ATTORNEY

UNITED STATES PATENT OFFICE.

JOHN SIGWALT AND ARTHUR M. WILLARD, OF CHICAGO, ILLINOIS.

DESIGN FOR A HAND SEAL-PRESS BODY.

SPECIFICATION forming part of Design No. 32,214, dated February 13, 1900.

Application filed November 13, 1899. Serial No. 736,899. Term of patent 7 years.

To all whom it may concern:

Be it known that we, JOHN SIGWALT and ARTHUR M. WILLARD, citizens of the United States, residing at Chicago, in the county of Cook and State of Illinois, have invented and produced a new and original Design for a Hand Seal-Press Body, of which the following is a specification, reference being had to the accompanying drawings, which form a part thereof.

Figure 1 is a view in side elevation of a hand seal-press body, showing our new design. Fig. 2 is a top plan view, in part sectional, taken on the line X X of Fig. 1.

As shown in the drawings, the material feature of our design consists of a twig B, provided with leaves C, disposed on each side of the body A, the twigs converging from a stem or point of conjunction B' at or near the rear lower position of the body and extending up-

wardly forward to or about the point α , as indicated. Twigs B, stem B', and leaves C are essentially integral of the body, the former, the stem B', and the outer margins of the leaves, together with their stem connections 25 with the twigs, being arranged to project beyond the contiguous perimeter of the body A, with the interior portions C' of the leaves concaved or recessed, as shown.

Having described our design, what we claim 30 as new, and desire to secure by Letters Patent, is—

The design for a hand seal-press body, as herein shown and described.

JOHN SIGWALT.
ARTHUR M. WILLARD.
